UNITED STATES PATENT OFFICE.

JERROLD F. WALTON, OF STURGIS, MICHIGAN.

ADJUSTABLE CHAIR.

1,079,528.

Specification of Letters Patent. Patented Nov. 25, 1913.

Application filed March 29, 1909. Serial No. 486,469.

To all whom it may concern:

Be it known that I, JERROLD F. WALTON, a citizen of the United States, residing at the city of Sturgis, county of St. Joseph,

5 State of Michigan, have invented certain new and useful Improvements in Adjustable Chairs, of which the following is a specification.

This invention relates to improvements in 10 adjustable chairs.

The main objects of this invention are: First, to provide an improved chair in which the back can be easily adjusted by the occupant of the chair. Second, to provide an 15 improved chair having an adjustable back in which the adjusting mechanism is so arranged as not to disfigure the chair. Third, to provide an improved chair having an adjustable back which is very simple in its 20 mechanism, and one in which the back, at the same time, is effectively supported.

Further objects, and objects relating to structural details, will definitely appear from the detailed description to follow.

25 I accomplish the objects of my invention by the devices and means described in the following specification.

The invention is clearly defined and pointed out in the claims.

30 A structure embodying the features of my invention is clearly illustrated in the accompanying drawing, forming a part of this specification, in which:

Figure 1 is detail vertical section of a 35 structure embodying the features of my invention, portions being broken away to better show the arrangement of the parts. Fig. 2 is an inverted plan view thereof. Fig. 3 is an enlarged detail section corresponding 40 to the section of Fig. 1. Fig. 4 is a horizontal section, taken on a line corresponding to line 4-4 of Fig. 3. Fig. 5 is an enlarged detail taken on a line corresponding to line 5-5 of Fig. 3. Fig. 6 is an enlarged detail 45 taken on a line corresponding to line 6-6 of Fig. 1, showing the finger piece rod and its arrangement. Fig. 7 is an enlarged detail taken on a line corresponding to line 7-7 of Fig. 6, showing the supporting 50 spring for the release rod.

In the drawing, similar reference characters refer to similar parts throughout the several views, and the sectional views are taken looking in the direction of the little 55 arrows at the ends of the section lines.

Referring to the drawing, the chair frame

preferably consists of the rear posts 1 and the front posts 2, which are extended to form the front and rear legs of the chair. On the upper ends of the posts are arms 3. The posts are connected by the side frame 60 pieces 4 and the front and rear frame pieces 5 and 6, respectively. The frame is also preferably provided with a horizontally-arranged piece 7 for supporting the adjusting mechanism, as appears in Figs. 1 and 2.

The back is preferably made up of side pieces or side bars 8 connected by cross pieces 9. The back is hinged at its lower end, suitable hinge members not illustrated 70 being provided on the frame for the pivots 11. The mechanism for adjustably supporting the back preferably comprises the arm 12, which is preferably secured to the back by arranging the same vertically through the cross pieces 9 of the back. The arm projects downwardly within the frame piece 6 so that its lower end projects below the frame piece 7 which is provided with a slot 13 for the arm (see Fig. 1) so that movement of the arm is permitted. This arrangement of the parts is illustrated and claimed 80 in my application for patent filed concurrently herewith. Connected to the lower end of the arm by means of a suitable pivot, 85 as 14, is a link 15. This link is preferably formed of a strip of sheet metal bent into a U-shape, as is clearly illustrated in Fig. 5. The forward end of the link is adjustably supported by means of the rack 16. This 90 rack is faced upwardly and preferably formed of two members arranged so that the end of the link lies between them. These rack members are preferably formed of one piece of metal bent into a loop, the rear 95 ends being turned horizontally to form the attaching parts 17, attaching screws 18 being arranged therethrough, as clearly appears in Fig. 2. When thus supported, this rack is formed of spring material so that 100 its forward end may be pushed downwardly to disengage the rack engaging pins 19 of the link 15, the pins being preferably formed of one piece arranged through the rack, as clearly appears in Fig. 5. 105

I preferably provide stop members 20, one at each side of the rack. These are preferably formed of pieces of wire, as illustrated, the ends of the wire being turned upwardly and driven into the frame piece 7. These 110 stops, limit the movement of the link and insure the withdrawal of the rack from the

rack engaging pins 19 of the link. The back is held normally forward by means of the springs 21 which are secured at their forward ends to the rack engaging pins 19 and at their rear ends to the rear frame piece 6, screw-eyes, as 22, being provided for their connection. These springs are preferably arranged to lift upwardly on the forward end of the link so that they tend to withdraw the rack engaging members from the rack. The upward movement of the link is, however, limited by the frame piece 7 so that, when the rack is in its normal position, the springs cannot disengage the link therefrom.

15 The release rod 23 is secured at one end to one of the side pieces 4 of the frame and to the forward end of the rack (see Fig. 2). The finger piece rod 24 is provided with an eye 25 at its lower end to receive the release rod, the upper end of the finger piece rod being arranged through one of the arms 3 of the chair. The finger piece 26 is preferably in the form of a button and arranged 20 in a countersink 27 (see Fig. 7). The rod is preferably arranged on the inside of the side piece 4 of the frame, being offset so that it lies at the rear of one of the front posts 2 and is thus in an inconspicuous position. 25 The release rod is held yielding upward and through the rod the rack is held yielding upward by means of the spring 28. This spring is preferably a rod spring secured at one end by means of the suitable 30 staples, 29, on the inside of one of the frame pieces 4, its other end being arranged under the release rod. The spring is preferably provided with a coil 30, illustrated. The advantage of this form of spring is that a 35 long spring can thus be had for the release rod, and, at the same time, it is so arranged that it does not interfere with the upholstery of the chair and is inconspicuous.

40 By arranging the parts as I have illustrated and described, I secure a chair which is very economical in structure, and, at the same time, neat and attractive in appearance. Also it has the advantage of being very convenient to adjust.

45 50 Having thus described my invention, what I claim as new and desire to secure by Letters Patent, is:

1. In a chair, the combination with the frame, of a seat; a hinged back; a link having a pivot connection for its rear end to said back below its hinges and laterally-projecting pins at its forward end; an adjustable rack comprising a pair of members between which the forward end of said link 55 is arranged; a pair of springs connected to said pins on said link and to said frame; said springs being arranged to lift upwardly on the forward end of said link; a pair of stop members arranged on either side of said 60 rack to embrace said pins on said link; and 65 means for adjusting said rack to release said link.

means for adjusting said rack to release said link.

2. In a chair, the combination with the frame, of a seat; a hinged back; a link having a pivot connection for its rear end to 70 said back below its hinges and laterally-projecting pins at its forward end; an adjustable rack comprising a pair of members between which the forward end of said link is arranged; a pair of springs connected to 75 said pins on said link and to said frame, said springs being arranged to lift upwardly on the forward end of said link; and means for adjusting said rack to release said link.

3. In a chair, the combination with the 80 frame, of a seat; a hinged back; a link having a pivot connection for its rear end to said back below its hinges and laterally-projecting pins at its forward end; an adjustable rack comprising a pair of members 85 between which the forward end of said link is arranged; a pair of stop members arranged on either side of said rack to embrace said pins on said link; and means for adjusting said rack to release said link.

4. In a chair, the combination with the frame, of a seat; a hinged back; a link having a pivot connection for its rear end to said back below its hinges and laterally-projecting pins at its forward end; an adjustable rack comprising a pair of members between which the forward end of said link is arranged; and means for adjusting said 90 rack to release said link.

5. In a chair, the combination with the 100 frame, of a seat; a hinged back; a link having a pivot connection for its rear end to its said back below its hinges, said link being formed of a piece of sheet metal bent into U-shape and having laterally-projecting 105 pins at its forward end; a rack comprising a pair of members between which the forward end of said link is arranged, said rack being formed of a piece of sheet metal bent into a loop, the rear ends of which are 110 turned horizontally and secured to said frame, whereby said rack is adjustably supported; and means for adjusting said rack to release said link.

6. In a chair, the combination with the 115 frame, of a seat, a hinged back; a link having a pivot connection for its rear end to said back below its hinges having laterally-projecting pins at its forward end; a rack comprising a pair of members between which the forward end of said link is arranged, said rack being formed of a piece of sheet metal bent in a loop, the rear ends of which are turned horizontally and secured to said frame, whereby said rack is adjustably supported; and means for adjusting said rack to release said link.

7. In a chair, the combination with the frame, of a seat; a hinged back; a link having a pivot connection for its rear end to 120

said back below its hinges, said link being formed of a piece of sheet metal bent into a U-shape and having laterally projecting arms at its forward end; and a rack comprising a pair of members between which the forward end of said link is arranged, and means for adjusting said rack to release said link.

8. In a chair, the combination with the frame, of a seat, a hinged back; a link having a pivot connection for its rear end to said back below its hinge, having laterally-projecting pins at its forward end; and a rack comprising a pair of members between which the forward end of said link is arranged, and means for adjusting said rack to release said link.

9. In an arm chair, the combination with the frame, of a hinged back; a downwardly-projecting arm on said back; an adjustable rack; a link having a rack engaging member at its forward end pivoted on said arm; a transversely-arranged release rod for said rack connected to said rack and to said frame at one end; a spring for holding the

other end of said rod yieldingly upward; and a finger piece rod for said release rod arranged through an arm of the chair and within said frame, said finger piece rod being provided with a finger piece arranged in a countersink in the said arm.

10. In an arm chair, the combination with the frame, of a hinged back; a downwardly-projecting arm on said back; an adjustable rack; a link having a rack engaging member at its forward end pivoted on said arm; a transversely-arranged release rod for said rack connected to said rack and to said frame at one end; a spring for holding the other end of said rod yieldingly upward; and a finger piece rod for said release rod arranged through an arm of the chair.

In witness whereof, I have hereunto set my hand and seal in the presence of two witnesses.
